Japanese Office Action issued in Japanese Design Application No. 2013-006143 dated Jul. 16, 2013 with English Translation.

Primary Examiner — Elizabeth J Oswecki(74) *Attorney, Agent, or Firm* — McDermott Will & Emery LLP**CLAIM**

The ornamental design for a semiconductor device, as shown and described.

DESCRIPTION

FIG. 1 is a perspective view of a semiconductor device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.
